UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

RADIOBROADCAST DISTRIBUTING SYSTEM.

Application filed November 25, 1925. Serial No. 71,456.

My invention relates to radio broadcast distribution, and its objects are secrecy, flexibility and certainty. It achieves transmission by what I have called a silent wave, because there would be no intelligible manifestation in any ordinary receiving instrument of the modulations being transmitted by this system. It supplies the final link in the chain of operations of the system disclosed in my prior copending application, Serial No. 746,357, filed October 28, 1924, patented July 5, 1927, as No. 1,635,153, in which it was stated that the use of double modulation would enable secrecy to be attained, and in which the selection of programs with the fixed or flat tuned instrument was attained by tuning the secondary circuit so as to take off and select one of several intermediate frequency carrier waves, all modulated on a carrier wave or waves of the same standard high frequency, to which the receivers are tuned, and each bearing a different audio frequency modulation of its own.

I attain my objects by first producing by modulation at audio frequencies in the presence of an intermediate superaudio frequency source, a band of frequencies representing the said superaudio frequency plus or minus the constantly changing modulating audio frequencies, thereby in effect producing frequency modulation. I then modulate these waves at frequencies which are constantly changing as their audio frequency component changes upon a wave of constant high frequency, which thereupon becomes also variable in its frequency characteristic in proportion to the strength of the carrier with respect to the strength of the variable frequency modulating band. I then radiate this doubly modulated carrier. At the receiving station I first detect and demodulate the high frequency carrier, then by means of a suitable composition circuit, I combine the resultant wave band with a wave at the same frequency as that of the original intermediate frequency superaudio source, then finally detect and demodulate the resultant intermediate frequency carrier to obtain the original audio modulations.

As a modified method of practicing the invention, I may follow the foregoing, but without having a separate source to supply the intermediate frequency at the receiving

station. Instead thereof, I may separately modulate the original intermediate frequency carrier wave on a suitable high frequency carrier wave, radiate the same, receive it at the receiving station, demodulate, and apply the resultant intermediate frequency current to the composition circuit to combine with the variable frequency wave band as before.

My invention is illustrated in the accompanying drawings, in which—

Fig. 1 is a diagram of a transmitting station equipped with a balanced primary modulator circuit, a band filter and a secondary modulator circuit of the Colpitts-Heising type by which a doubly modulated short wave carrier is radiated to the receiving station, having the characteristics of a variable frequency modulation instead of the usual variable amplitude modulation.

Fig. 2 is a diagram of a receiving station adapted to cooperate with the sending station of Fig. 1, and provided with a source of alternating current capable of giving the same frequency as that originally supplied in the primary modulating circuit of Fig. 1.

Fig. 3 is a diagram of a modified arrangement, using the simple Heising method for double modulation, with an interposed filter.

Fig. 4 is a schematic diagram showing the same system as in Figs. 1 and 2, but with separate radio transmission of the original low frequency carrier wave, for supply to the demodulator at the receiving station.

Fig. 5 is a schematic diagram illustrating a modification of the variable frequency band modulation, using balanced modulating circuits with band filters for both modulators.

Referring to Figs. 1 and 2, X represents a transmitting station and Y represent a receiving station. In Fig. 1, x is a balanced modulator circuit in which there is normally no current flow, the source S of alternating superaudio frequency being connected by coupler 6 to the neutral member 7 of the balancing circuits 2—3, through which the same potential is maintained on the grids of both vacuum tubes V and V'. When variable currents are caused to flow in the audio frequency circuit 1, as by microphone T, the balance is disturbed, and plate circuits 4—5—7^a carry bands of waves of the frequency of S plus and minus the varying audio modulation frequencies, but

without any unmodulated current of frequency S above. 10 is a filter by which one band may be suppressed, and one band only passed to the secondary modulator x' . Couplings 8 and 11 are of any desired and suitable type. The modulator circuit 12 and tube V^2 and the oscillator circuit 13 and tube S^2 are of a usual type, adapted to impose the wave band passed through coupling 11, on the oscillatory carrier wave produced by S^2 , and to radiate the latter from antenna circuit 14.

The source S may generate current of a frequency from 25 to 100 kilocycles per second, which I have designated herein as "superaudio" frequencies or "IF", i. e. intermediate frequencies, lying between audio and radio frequency limits.

The source S^2 generates oscillating current at radio frequency, for example, at a frequency between 500 and 3,000 kilocycles per second.

It is to be understood that these figures are given for purposes of definition of the invention, and not for limitation, as they may be varied without departure therefrom if the principle of band modulation or a radio carrier not the same as the original carrier is maintained. As a matter of fact, the oscillator S^2 and its immediate circuit may be replaced by a harmonic generator, or harmonic producer such as a distortion tube, taking its initial energization from the low frequency generator S . This would reduce the modulator x' practically to coupled amplifier and power circuits.

In Fig. 2, y is the first demodulator and y' the second demodulator. S' is a source of superaudio frequency current equivalent to that supplied by generator S . It is shown as coupled to the second detector circuit 21 by a coil in inductive relation to the coils of the coupler 28, but may be connected instead through a separate composition circuit 25, (see Fig. 4), interposed between the elements of coupling 28 in Fig. 2. The antenna circuit 15 is tuned, as is the input circuit 17, to receive the band modulated carrier radiated from 14 in Fig. 1. The first detector V^4 demodulates this radio carrier, and passes the modulated variable frequency band through coupler 28 to the input 21 of the second detector V^5 , current from the source S' being also supplied through said circuit to the grid circuit 20. This IF or superaudio frequency current acts upon the incoming modulated wave band to translate it from a band of variable frequencies to a variable amplitude modulation on the IF carrier current, which is rectified by the second detector V^5 , and the signal modulations passed through plate circuit 22 to a responsive device 23.

Fig. 3 shows both the first modulator circuit x and the second modulator x' as of

the known Heising type, with an Arnold filter 10^x interposed between them to suppress the unmodulated carrier current supplied by oscillator S , and amplifiers for the band passed to the modulator tube V^2 . Fig. 70 1, however, is the preferred arrangement.

In my application filed concurrently herewith, Serial No. 71,457, filed November 25, 1925, I have shown an arrangement of transmitting and receiving stations similar to 75 that shown herein, but with a wire circuit conducting current from the source S , (Fig. 1), to the composition circuit or coil 28 or 25 (Figs. 2 and 4) so that the generator S' is unnecessary, and the frequencies S and S' 80 in circuits 7 and 21 are identical. In the present case I do not show any wire circuit, but in order to ensure the synchronism and phase identity of the waves supplied to the modulator x , as by S , and to the circuit 21 85 or 25 as by S' , I may modulate a second radio frequency carrier wave with the IF or intermediate frequency from generator 90 S and radiate the same to stations Y where it is demodulated and the IF wave amplified and supplied to composition circuit 25 or 21, instead of current separately generated at 95 S' . Such an arrangement is schematically illustrated in Fig. 4, in which, as before, X is a transmitting station and Y is a receiving station. At station X the rectangle x represents the balanced modulator the same as that shown in Fig. 1, supplied with intermediate frequency or superaudio potential by generator S . The microphone sets up 100 audio frequency alternations in the circuits 2 and 3 which function in the presence of said superaudio potential to produce a wave band of frequencies varying in accordance with the audio or other modulation imposed 105 on circuit 1. This band passes through coupler 8 to the band filter and amplifier 10, thence through coupler 11 to the modulator and amplifier x' whereby it is modulated as before on a radio carrier wave and finally 110 radiated from the circuit 14.

In addition to its connection through coupler 6 to the modulator x , the generator S has a series coupler connection 11^x with a modulator and radiator x^2 , supplied with 115 high or radio frequency carrier current by generator S^{10} . This unit x^2 acts to impose the unmodulated constant frequency IF wave due to S on the radio carrier wave due to S^{10} , and then to radiate this carrier modulated with a carrier.

At station Y the operation of the first and second demodulations y and y' is the same as before described, but instead of a separate carrier wave generator for the composition circuit 25, I provide the separate demodulator and amplifier unit y^2 , which receives the wave radiated by x^2 , demodulates the same, and after amplification to the extent desired, supplies the IF frequency wave 130

thus derived from S, through circuit 26 and 5 coupler 24 to the composition circuit 25, where it acts upon the wave and passed by coupling 20, to translate the same from a band of variable frequencies to amplitude 10 modulations on the IF carrier, which being passed through coupling 20^a to the second detector circuit y' is demodulated and the 15 signal modulations communicated, with or without amplification, to the responsive device 23. Thus, the wave band carrying the 20 signal is radiated on one carrier, and the IF wave on which the wave band was modulated, is itself radiated on another carrier, 25 both are received and separately detected and then combined.

In Fig. 5 I have shown schematically a 20 modified arrangement of transmitting and receiving apparatus in which balanced modulator circuits similar to that marked α in Fig. 1 are used for both α and α' , with wave filters and amplifiers 10 and 100 for their 25 respective outputs. The parts are marked with the same numerals and letters as before. Modulations or signals as by T, are 30 propagated in the circuits 2-3 and functioning in presence of superaudio or IF alternating potentials from generator S produce variable frequency bands at 8 which a 35 single side band is passed by 10, amplified if desired, and through coupler 11 communicated to circuits 200 and 300, second modulator α' which are identical with circuits 1 and 2 of α . This wave band modulation, 40 functioning in the presence of radio frequency alternating potential from generator S³, produces at 11^a two side bands, from 45 which one is again filtered out and amplified at 100 and radiated from the circuit 14. The receiver Y has an antenna circuit 15 tuned to receive the compound band of 50 variable frequency, and an amplifier and composition circuit 25, supplied by generator S⁴ with current of frequency the same as S³. The effect of this composition is to pass 55 through coupler 20^b a carrier of frequency S⁴ carrying amplitude oscillations representing the modulated band due to α . The first 60 detector y detects off this IF wave band, which varies in frequency in accordance with the variations in the signal frequency imposed by T or other signal transmission. This band is then passed through coupler 20^c to amplifier and composition circuit 250 (similar to 25) supplied by generator S⁵ with intermediate frequency current of the 65 same frequency as S, and the resultant modulated current is passed through coupler 20^d to the final detector and demodulator y' which delivers the signal modulations to the 70 responsive device 23.

In this circuit of Fig. 5, it is necessary to

have perfect synchronism and phase identity 65 as between each of two pairs of operating currents of IF and radio frequency respectively. This makes it very desirable to use a means of supplying the same current or potential from generator S to both α and α' (through 250) and from generator S³ to both α' and α (through 25). Such a means is 70 the wire circuit or network described in my application Serial No. 71,457, filed November 25, 1925, above referred to; or the method of radiating the intermediate frequency carrier shown in Fig. 4 herein. The use of 75 such means I consider novel and original with myself and to be claimed accordingly.

It will be understood that all proper expedients and agencies known in the art are 80 contemplated and to be applied to these circuits in practice, such as suitable filters, amplifiers, current control devices, etc., none of 85 which I have shown in detail, for the sake of simplicity.

What I claim is:

1. A radio broadcasting system comprising a primary or audio frequency modulator adapted to function in the presence of an alternating superaudio frequency carrier potential, to produce a band of superaudio frequencies varying in accordance with the variations in frequency of the audio modulations, and a secondary or intermediate frequency modulator adapted to impose said modulated waves upon a radio frequency carrier 90 wave, and a radiator for radiating the same, means to impose an unmodulated wave equivalent to the original superaudio carrier, as a modulation on a radio frequency carrier wave and to radiate the same, with a receiving station equipped with a first and a second demodulating circuit, and means to demodulate the last named carrier and to supply the intermediate frequency or superaudio component thereof to the said second demodulating circuit together with the audio modulated wave band from the first demodulating circuit.

2. The method of radio transmission of 100 signals which consists in doubly modulating a carrier wave by first modulating signals on a relatively low frequency carrier and suppressing the unmodulated carrier so as to leave only a side band, and then modulating this side band upon a high frequency carrier, and radiating the same, while simultaneously imposing the unmodulated intermediate frequency carrier upon a separate high frequency carrier and radiating the 105 same.

In testimony whereof I hereunto affix my signature.

EDWARD E. CLEMENT.
